[57] **CLAIM**

The ornamental design for an inline roller skate wheel frame, as shown and described.

DESCRIPTION

FIG. 1 is a right side elevational view of a wheel frame showing our new design, the broken line showing of the boot is for illustrative purposes only and forms no part of the claimed design;

FIG. 2 is a front end elevational view of the wheel frame shown in FIG. 9;

FIG. 3 is a rear end elevational view thereof;

FIG. 4 is a left side elevational view thereof;

FIG. 5 is a top plan view thereof;

FIG. 6 is a bottom plan view thereof;

FIG. 7 is a front isometric view thereof; and,

FIG. 8 is front isometric view of a modified embodiment of the design shown in FIGS. 1-7.
